UNITED STATES PATENT OFFICE.

ZACHARIAH XEVERS, OF SANTA CRUZ, CALIFORNIA.

SASH LOCK AND HOLDER.

No. 846,176.

Specification of Letters Patent.

Patented March 5, 1907.

Application filed December 11, 1906. Serial No. 347,324.

To all whom it may concern:

Be it known that I, ZACHARIAH XEVERS, a citizen of the United States, residing at Santa Cruz, in the county of Santa Cruz and State of California, have invented certain new and useful Improvements in Sash Locks and Holders; and I do hereby declare that the following is a full, clear, and exact description of the same, reference being had to the annexed drawings, making a part of this specification, and to the letters and figures of reference marked thereon.

The present invention has for its object to provide a device that will serve effectually and successfully as a burglar-proof and an antirattler holder for the sashes of windows and employed as a means for regulating the air-supply in a room and enabling the windows to be left partly open and still be secure from intruders and burglars.

The invention consists in a device of the above character constructed substantially as shown in the drawings and hereinafter described and claimed.

Figure 1 of the drawings is a perspective view showing the holder secured to one of the sashes and in an operative position, a portion of the window-frame and upper and lower sashes being shown; Fig. 2 a side elevation of the holder, partly in section.

In the accompanying drawings, A represents a portion of a window-frame, and B C the upper and lower sashes, respectively, the holder being applied to the lower sash either on the right or left, as found most desirable, this being left entirely to the discretion of the user.

The body or base of the holder may be cast of suitable metal or of malleable iron or of any suitable material found most desirable, said body being bent upon itself at or near its center to form a base D, which has a suitable hole through the same to receive a fastening-screw *a* to secure it to the upper edge of the sash.

A downwardly-extending lip F is formed from the rectangular strip of metal from which the base D is constructed and has a hole or perforation to receive a fastening-screw *c* as a means for fastening it to the lower sash, as shown in Fig. 1 of the drawings.

The standard E is formed near the center

or upper part of the holder and supports a screw-rod G, the threads thereof engaging the threads of a screw-hole in the standard, 55 so that the rod may be moved in a direction to or from the sash and may be provided with a thumb-piece *e* for convenience of turning it. To the inner end of the rod G is swiveled or otherwise connected a clamping-head H, which is preferably of malleable metal, with or without the cushion I, as found preferable, said cushion being of leather, rubber, or other resilient material that will not mar or otherwise injure the painted surface of the sash. 65

When the screw-rod is moved in the direction of the sash or toward the same, it will force the contacting plate or cushion into intimate contact with the upper sash, causing 70 it to bind tightly against the sash-guide and prevent lateral movement of the sash, and if the screw-rod be moved with sufficient force the holder will serve as a lock to prevent the raising or lowering of either sash, while the 75 window may be left open a little at the top or bottom, or both, for ventilating purposes, thereby providing an antirattling means and a burglar-proof holder therefor which secures an absolute lock for the sash against raising 80 it from the outside, besides insuring the sashes being perfectly stationary against moving in their guides, which would cause a rattling thereof. 85

Having now fully described my invention, 85 what I claim as new, and desire to secure by Letters Patent, is—

A ventilating sash lock and holder comprising a rectangular strip of metal bent upon itself to provide a base of double thickness 90 and the ends thereof extending upward and downward to form a standard and a fastening-clip respectively, the lower portion of the double base extending outward and forward beyond the standard and terminating in the 95 clip, and a suitable screw-rod with clamping-head supported by the standard, substantially as and for the purpose set forth.

In testimony whereof I affix my signature in presence of two witnesses.

ZACHARIAH XEVERS.
